UNITED STATES PATENT OFFICE.

MILTON D. MESEROLE, OF MILFORD, CONNECTICUT, ASSIGNOR TO HAYES & MESEROLE MFG. CO., OF MILFORD, CONNECTICUT, A FIRM.

HAIR CURLER.

1,416,301.

Specification of Letters Patent. Patented May 16, 1922.

Application filed October 22, 1921. Serial No. 509,666.

To all whom it may concern:

Be it known that I, MILTON D. MESEROLE, a citizen of the United States, residing at Milford, in the county of New Haven and 5 State of Connecticut, have invented a new and useful Improvement in Hair Curlers; and I do hereby declare the following, when taken in connection with the accompanying drawings and the characters of reference 10 marked thereon, to be a full, clear, and exact description of the same, and which said drawings constitute part of this application, and represent, in—

Fig. 1, a plan view of a hair curler constructed in accordance with my invention.

Fig. 2, a side view of the same.

Fig. 3, a sectional view on the line 3—3 of Fig. 1.

Fig. 4, a side view of the device with the 20 tension in its open position, showing it turned in opposite directions by broken lines.

This invention relates to improvement in hair curlers, and particularly to curlers which are formed from metal, the object of 25 the invention being a simple arrangement of parts which can be readily formed in automatic machines and which is especially convenient for use, and the invention consists in the construction and arrangement of parts 30 as will be hereinafter described and particularly recited in the claims.

In carrying out my invention, I preferably form the frame from a strip of wire, the central portion of which forms a rear 35 bar 5, from which sides 6 and 7 project, the ends 8 and 9 being turned inward to meet and form a rectangular frame. The tongue is formed from a single piece of wire doubled at the center to form a tip 10, the ends 40 of the tongue being formed with eyes 11 and 12 which are bent around the bar 5. The tip 10 is flattened, as are also the adjacent portions of the side bars 6 and 7, and folded around the side bars at the flattened portions 45 is a slide 13 formed from a strip of metal folded into box shape, with a centrally arranged lip 14, which is turned in-

ward between the bars 6 and 7, this slide being adapted to move on the bars and pass over the tip 10, so as to hold the tip between 50 the bars. It is obvious that the member may be struck up from sheet-metal if desired.

It will be noted that in this construction, the tongue may swing in either direction, so 55 that in use it is not necessary to hold the device in one particular position. The use of these devices is too well known to require description. It will be seen that the parts of the device are readily formed and 60 assembled by automatic machinery, so they can be produced at a very low cost, and as the tongue is firmly locked in the frame, danger of disengagement is avoided. It will 65 be understood that the frame and tongue are formed from spring metal, so as to give the necessary tension and yield when a mass of hair is wound upon them.

I claim:

1. A hair curler, comprising a frame 70 formed from a single piece of wire bent to provide a rear bar and two sides, the ends of the wire turned inward, a tongue hinged to the said rear bar, and a slide mounted on the side bars of the frame and adapted to 75 extend over the tip of the tongue.

2. A hair curler comprising a frame formed from a single piece of wire bent to provide a rear bar, a tongue formed from a single piece of wire, the ends of which are 80 hinged to the said rear bar, the sides of the frame and the tip of the tongue flattened, and a slide mounted on the flattened portion of the frame and adapted to extend over the tip of the tongue, the said slide also formed 85 with a lip projecting inward between the sides of the frame.

In testimony whereof, I have signed this specification in the presence of two subscribing witnesses.

MILTON D. MESEROLE.
